(57) **ABSTRACT**

A turbine airfoil assembly for installation in a gas turbine engine. The airfoil assembly includes an endwall and an airfoil extending radially outwardly from the endwall. The airfoil includes pressure and suction sidewalls defining chordally spaced apart leading and trailing edges of the airfoil. An airfoil mean line is defined located centrally between the pressure and suction sidewalls. An angle between the mean line and a line parallel to the engine axis at the leading and trailing edges defines gas flow entry angles, α , and exit angles, β . Airfoil inlet and exit angles are substantially in accordance with inlet angle values, α , and exit angle values, β , set forth in one of Tables 1, 2, 3, and 4.

TURBINE AIRFOIL WITH OPTIMIZED AIRFOIL ELEMENT ANGLES

CROSS REFERENCE TO RELATED APPLICATIONS

This application claims the benefit of U.S. Provisional Patent Application Ser. No. 62/094,107, filed Dec. 19, 2014, entitled "Turbine Airfoil Unique Aero Configuration", the entire disclosure of which is incorporated by reference herein in its entirety.

BACKGROUND

1. Field

The present invention relates to turbine vanes and blades for a gas turbine stage and, more particularly, to third and fourth stage turbine vane and blade airfoil configurations.

2. Description of the Related Art

In a turbomachine, such as a gas turbine engine, air is pressurized in a compressor then mixed with fuel and burned in a combustor to generate hot combustion gases. The hot combustion gases are expanded within the turbine section where energy is extracted to power the compressor and to produce useful work, such as turning a generator to produce electricity. The hot combustion gas travels through a series of turbine stages. A turbine stage may include a row of stationary vanes followed by a row of rotating turbine blades, where the turbine blades extract energy from the hot combustion gas for powering the compressor, and may additionally provide an output power.

The overall work output from the turbine is distributed into all of the stages. The stationary vanes are provided to accelerate the flow and turn the flow to feed into the downstream rotating blades to generate torque to drive the upstream compressor. The flow turning in each rotating blade creates a reaction force on the blade to produce the torque. The work transformation from the gas flow to the rotor disk is directly related to the engine efficiency, and the distribution of the work split for each stage and the associated airfoil angles may be controlled by the vane and blade design for each stage and studied and selected for each unique engine design. Each row of airfoils has a unique set of inlet angles at the airfoil leading edge and a set of exit angles at the airfoil trailing edge. These angles are varied along the radial direction from the root to the tip.

SUMMARY

In one aspect of the present invention, a turbine airfoil assembly for installation in a gas turbine engine having a longitudinal axis, the turbine airfoil assembly including an endwall for defining an inner boundary for an axially extending hot working gas path, and an airfoil extending radially outwardly from the endwall, the airfoil having an outer wall comprising a pressure sidewall and a suction sidewall joined together at chordally spaced apart leading and trailing edges of the airfoil, an airfoil mean line is defined extending chordally and located centrally between the pressure and suction sidewalls, airfoil inlet and exit angles are defined at the airfoil leading and trailing edges that are substantially in accordance with inlet angle values, α , and exit angle values, β , set forth in one of Tables 1, 2, 3, and 4, where the inlet and exit angle values are generally defined as angles between a line parallel to the longitudinal axis and the airfoil mean line lying in an X-Y place of an X, Y, Z Cartesian coordinate system in which Z is a dimension

perpendicular to the X-Y plane and extends radially relative to the longitudinal axis, and wherein each of the inlet and exit angle values is defined with respect to a distance from the endwall corresponding to a Z value that is a distance of a total span of the airfoil from the endwall with the distances being joined smoothly with one another to form a complete airfoil shape.

In another aspect of the present invention, third and fourth stage vane and blade airfoil assemblies in a gas turbine engine having a longitudinal axis, each airfoil assembly including:

an endwall for defining an inner boundary for an axially extending hot working gas path, and an airfoil extending radially outwardly from the endwall, the airfoil having an outer wall comprising a pressure sidewall and a suction sidewall joined together at chordally spaced apart leading and trailing edges of the airfoil, an airfoil mean line is defined extending chordally and located centrally between the pressure and suction sidewalls, airfoil inlet and exit angles are defined at the airfoil leading and trailing edges that are substantially in accordance with inlet angle values, α , and exit angle values, β , where the inlet and exit angle values are generally defined as angles between a line parallel to the longitudinal axis and the airfoil mean line lying in an X-Y plane of an X, Y, Z Cartesian coordinate system in which Z is a dimension perpendicular to the X-Y plane and extends radially relative to the longitudinal axis, and wherein each of the inlet and exit angle values is defined with respect to a distance from the endwall corresponding to a Z value that is a percentage of the total span of the airfoil from the endwall, wherein:

- a) the inlet angle values, α , and exit angle values, β , for the third stage vane are as set forth in Table 1;
- b) the inlet angle values, α , and exit angle values, β , for the third stage blade are as set forth in Table 2;
- c) the inlet angle values, α , and exit angle values, β , for the fourth stage vane are as set forth in Table 3;
- d) the inlet angle values, α , and exit angle values, β , for the fourth stage blade are as set forth in Table 4.

In another aspect of the present invention, a turbine airfoil assembly for installation in a gas turbine engine having a longitudinal axis, the turbine airfoil assembly including an endwall for defining an inner boundary for an axially extending hot working gas path, and an airfoil extending radially outwardly from the endwall, the airfoil having an outer wall comprising a pressure sidewall and a suction sidewall joined together at chordally spaced apart leading and trailing edges of the airfoil, an airfoil mean line is defined extending chordally and located centrally between the pressure and suction sidewalls, airfoil exit angles are defined at the airfoil trailing edge that are substantially in accordance with exit angle values, β , set forth in one of Tables 1, 2, 3, and 4, where the exit angle values are generally defined as angles between a line parallel to the longitudinal axis and the airfoil mean line lying in an X-Y plane of an X, Y, Z Cartesian coordinate system in which Z is a dimension perpendicular to the X-Y plane and extends radially relative to the longitudinal axis, wherein each the exit angle value is defined with respect to a distance from the endwall corresponding to a Z value that is a distance of a total span of the airfoil from the endwall with the distances being joined smoothly with one another to form a complete airfoil shape, and wherein each the airfoil exit angle is within about 1% of a respective value set forth in one of Tables 1, 2, 3, and 4.

These and other features, aspects and advantages of the present invention will become better understood with reference to the following drawings, description and claims.

BRIEF DESCRIPTION OF THE DRAWINGS

The invention is shown in more detail by help of figures. The figures show preferred configurations and do not limit the scope of the invention.

FIG. 1 is a cross-sectional view of a turbine section for a gas turbine engine;

FIG. 2 is a side elevational view of a third stage vane assembly formed in accordance with aspects of the present invention;

FIG. 3 is a perspective view of the vane assembly of FIG. 2;

FIG. 4 is a cross-sectional plan view of an airfoil of the vane assembly of FIG. 2;

FIG. 5 is a graphical illustration of entry and exit angles defined along the span of an airfoil for the vane assembly of FIG. 2;

FIG. 6 is a side elevational view of a third stage blade assembly formed in accordance with aspects of the present invention;

FIG. 7 is a perspective view of the blade assembly of FIG. 6;

FIG. 8 is a cross-sectional plan view of an airfoil of the blade assembly of FIG. 6;

FIG. 9 is a graphical illustration of entry and exit angles defined along the span of an airfoil for the blade assembly of FIG. 6;

FIG. 10 is a side elevational view of a fourth stage vane assembly formed in accordance with aspects of the present invention;

FIG. 11 is a perspective view of the vane assembly of FIG. 10;

FIG. 12 is a cross-sectional plan view of an airfoil of the vane assembly of FIG. 10;

FIG. 13 is a graphical illustration of entry and exit angles defined along the span of an airfoil for the vane assembly of FIG. 10;

FIG. 14 is a side elevational view of a fourth stage blade assembly formed in accordance with aspects of the present invention;

FIG. 15 is a perspective view of the blade assembly of FIG. 14;

FIG. 16 is a cross-sectional plan view of an airfoil of the blade assembly of FIG. 14; and

FIG. 17 is a graphical illustration of entry and exit angles defined along the span of an airfoil for the blade assembly of FIG. 14.

DETAILED DESCRIPTION

In the following detailed description of the preferred embodiment, reference is made to the accompanying drawings that form a part hereof, and in which is shown by way of illustration, and not by way of limitation, a specific embodiment in which the invention may be practiced. It is understood that other embodiments may be utilized and that changes may be made without departing from the spirit and scope of the present invention.

Broadly, an embodiment of the present invention provides a turbine airfoil assembly for installation in a gas turbine engine. The airfoil assembly includes an endwall and an airfoil extending radially outwardly from the endwall. The airfoil includes pressure and suction sidewalls defining

chordally spaced apart leading and trailing edges of the airfoil. An airfoil mean line is defined located centrally between the pressure and suction sidewalls. An angle between the mean line and a line parallel to the engine axis at the leading and trailing edges defines gas flow entry angles, α , and exit angles, β . Airfoil inlet and exit angles are substantially in accordance with inlet angle values, α , and exit angle values, β , set forth in one of Tables 1, 2, 3, and 4.

Referring to FIG. 1, a turbine section 12 for a gas turbine engine is illustrated. The turbine section 12 includes alternating rows of stationary vanes and rotating blades extending radially into an axial flow path 13 extending through the turbine section 12. In particular, the turbine section 12 includes at least a first stage formed by a first row of stationary vanes 14 and a first row of rotating blades 16, a second stage formed by a second row of stationary vanes 18 and a second row of rotating blades 20, a third stage formed by a third row of stationary vanes 22 and third row of rotating blades 24, and a fourth stage formed by a fourth row of stationary vanes 26 and a fourth row of rotating blades 28.

During operation of the gas turbine engine, a compressor (not shown) of the engine supplies compressed air to a combustor (not shown) where the air is mixed with a fuel, and the mixture is ignited creating combustion products comprising a hot working gas defining a working fluid. The working fluid travels through the stages of the turbine section 12 where it expands and causes the blades 16, 20, 24, 28 to rotate. The overall work output from the turbine section 12 is distributed into all of the stages, where the stationary vanes 14, 18, 22, 26 are provided for accelerating the gas flow and turn the gas flow to feed into the respective downstream blades 16, 20, 24, 28 to generate torque on a rotor 30 supporting the blades 16, 20, 24, 28, producing a rotational output about a longitudinal axis 32, of the engine, such as to drive the upstream compressor.

The flow turning occurring at each rotating blade 16, 20, 24, 28 creates a reaction force on the blade 16, 20, 24, 28 to produce the output torque. The work split between the stages may be controlled by the angular changes in flow direction effected by each of the vanes 14, 18, 22, 26 and respective blades 16, 20, 24, 28, which work split has an effect on the efficiency of the engine. In accordance with an aspect of the invention, a design for the third and fourth stage vanes 22, 26, and blades 24, 28, is provided to optimize or improve the flow angle changes through the third and fourth stages. Specifically, the design of the third and fourth stage vanes 22, 26 and blades 24, 28, as described below, provide a radial variation in inlet and exit flow angles to produce optimized flow profiles into an exhaust diffuser 34 downstream from the turbine section 12. Optimized flow profiles through the third and fourth stages of the turbine section 12 may facilitate a reduction in the average Mach number for flows exiting the fourth stage vanes 26, with an associated improvement in engine efficiency, since flow loss tends to be proportional to the square of the Mach number.

Referring to FIGS. 2 through 4, a configuration for the third stage vane 22 is described. The vanes 22 each include an outer wall comprising a generally concave pressure sidewall 38, and include an opposing generally convex suction sidewall 40. The sidewalls 38, 40 extend radially between an inner diameter endwall 42 and an outer diameter endwall 44, and extend generally axially in a chordal direction between a leading edge 46 and a trailing edge 48 of each of the vanes 22. The endwalls 42, 44 are located at opposing ends of the vanes 22 and are positioned at locations where they form a boundary, i.e., inner and outer boundaries, defining a portion of the flow path 13 for the working fluid.

Opposing radially inner matefaces **45a**, **47a** and radially outer matefaces **45b**, **47b** are defined by the respective inner and outer diameter endwalls **42**, **44** of the airfoil structure **36**.

FIG. 4 illustrates a cross section of one of the vanes **22** at a radial location of about 50% of the span, S_{V3} , along the Z axis of a Cartesian coordinate system that has orthogonally related X, Y, and Z axes, wherein the Z axis extends perpendicular to a plane normal to a radius from the longitudinal axis **32** of the engine i.e., normal to a plane containing the X and Y axes, and generally parallel to the span, S_{V3} , of the airfoil for the vane **22**. It should be noted that the matefaces **45a**, **47a**, and **45b**, **47b** are shown herein (in FIG. 3) as extending at an angle relative to the direction of the longitudinal axis **32**.

The cross section of FIG. 4 lies in the X-Y plane. As seen in FIG. 4, the vane **22** defines an airfoil mean line, C_{V3} , comprising a chordally extending line at a central or mean location between the pressure and suction sidewalls **38**, **40**. At the leading edge **46**, a blade metal angle of each of the surfaces of the pressure and suction sides **38**, **40** adjacent to the leading edge **46** is provided for directing incoming flow to the vane **22** and defines an airfoil leading edge (LE) or inlet angle, α . The airfoil inlet angle α , is defined as an angle between a line 32_P parallel to the longitudinal axis **32** and an extension of the airfoil mean line, C_{V3} , at the leading edge **46**, i.e., tangential to the line C_{V3} , at the airfoil leading edge **46**.

At the trailing edge **48**, a blade metal angle of the surfaces of the pressure and suction sides **38**, **40** adjacent to the trailing edge **48** is provided for directing flow exiting from the vane **22** and defines an airfoil trailing edge (TE) or exit angle, β . The airfoil exit angle, β , is defined as an angle between a line 32_P parallel to the longitudinal axis **32** and an extension of the airfoil mean line, C_{V3} , at the trailing edge **48**, i.e., tangential to the line C_{V3} at the airfoil trailing edge **48**.

The inlet angles, α , and exit angles, β , for the airfoil of the vane **22** are as described in Table 1 below. The Z coordinate locations are presented as lengths along the total span of the vane **22**. The values for the inlet angles, α , and exit angles, β , are defined at selected Z locations spaced at increments along the span of the vane **22**, where 800 mm (of total value) is located adjacent to the inner endwall **42** and 1215 mm (of total value) is located adjacent to the outer endwall **44**. The inlet angles, α , and exit angles, β , are further graphically illustrated in FIG. 5.

TABLE 1

α -Metal Inlet Angle (deg) @ LE	Z LE (mm) @ LE	β -Metal Outlet Angle (deg) @ TE	Z TE (mm) @ TE
11.7	800	-62.79	800
17.2	840.43	-62.52	822.82
19.7	864.24	-63.06	847.22
24.7	913.25	-63.8	902.53
27.7	965.73	-64.6	963.8
27.7	1018.57	-65.9	1028.54
25.7	1068.68	-67.8	1094.99
20.7	1110.49	-69.3	1158.05
-0.3	1215	-69.58	1215

The inlet angle, α , is selected with reference to the flow direction coming from the second row blades **20**, and the exit angle, β , may be selected to provide a predetermined direction of flow into the third stage blades **24**.

The portions of the airfoil for the vane **22** described in Table 1 are provided with reference to a Cartesian coordinate system, as discussed above, that has orthogonally related X, Y and Z axes (FIG. 3) with the Z axis extending perpendicular to a plane normal to a radius from the centerline of the turbine rotor, i.e., normal to a plane containing the X and Y values, and generally parallel to the span, S_{V3} , of the airfoil for the vane **22**. The Z coordinate values in Table 1 have 800 mm at a radial location coinciding with the X, Y plane at the radially innermost aerodynamic section of the airfoil for the vane **22**, i.e., adjacent the inner endwall **42**, and are presented as lengths along the total span of the vane **22**. The X axis lies parallel to the longitudinal axis **32**, and the Y axis extends in the circumferential direction of the engine. Surface profiles at the various surface locations between the distances Z are connected smoothly to one another to form the leading edge section and trailing edge section of the airfoil.

Referring to FIGS. 6-9, a configuration for the third stage blade **24** is described. In particular, referring initially to FIGS. 6 and 7, a third stage blade airfoil structure **56** is shown including one of the airfoils or blades **24** adapted to be supported to extend radially across the flow path **13**. Referring additionally to FIG. 8, the blades **24** each include an outer wall comprising a generally concave pressure sidewall **58**, and include an opposing generally convex suction sidewall **60**. The sidewalls **58**, **60** extend radially outwardly from an inner diameter endwall **62** to a blade tip **64**, and extend generally axially in a chordal direction between a leading edge **66** and a trailing edge **68** of each of the blades **24**. A blade root is defined by a dovetail **65** extending radially inwardly from the endwall **62** for mounting the blade **24** to the rotor **30**. The endwall **62** is positioned at a location where it forms a boundary, i.e., an inner boundary, defining a portion of the flow path **13** for the working fluid.

FIG. 8 illustrates a cross section of the blade **24** at a radial location of about 50% of the span, S_{B3} (FIG. 6), along the Z axis of a Cartesian coordinate system that has orthogonally related X, Y and Z axes (FIG. 7), where the Z axis extends perpendicular to a plane normal to a radius from the longitudinal axis **32** of the engine i.e., normal to a plane containing the X and Y axes, and generally parallel to the span, S_{B3} , of the airfoil for the blade **24**. It should be noted that a central lengthwise axis **67** of the dovetail **65** is shown herein as extending at an angle relative to the direction of the longitudinal axis **32**.

The cross section of FIG. 8 lies in the X-Y plane. As seen in FIG. 8, the blade **24** defines an airfoil mean line, C_{B3} , comprising a chordally extending line at a central or mean location between the pressure and suction sidewalls **58**, **60**. At the leading edge **66**, a blade metal angle of each of the surfaces of the pressure and suction sides **58**, **60** adjacent to the leading edge **66** is provided for directing incoming flow to the blade **24** and defines an airfoil leading edge (LE) or inlet angle, α . The airfoil inlet angle, α , is defined as an angle between a line 32_P parallel to the longitudinal axis **32** and an extension of the airfoil mean line, C_{B3} , at the leading edge **66**, i.e., tangential to the line C_{B3} at the airfoil leading edge **66**.

At the trailing edge **68**, a blade metal angle of the surfaces of the pressure and suction sides **58**, **60** adjacent to the trailing edge **68** is provided for directing flow exiting from the blade **24** and defines an airfoil trailing edge (TE) or exit angle, β . The airfoil exit angle, β , is defined as an angle between a line 32_P parallel to the longitudinal axis **32** and an

extension of the airfoil mean line, C_{B3} , at the trailing edge **68**, i.e., tangential to the line C_{B3} at the airfoil trailing edge **68**.

The inlet angles, α , and exit angles, β , for the airfoil of the blade **24** are as described in Table 2 below. The Z coordinate locations are presented as lengths along the total span of the blade **24**. The values for the inlet angles, α , and exit angles, β , are defined at selected Z locations spaced at increments along the span of the blade **24**, where 810 mm (of total value) is located adjacent to the inner endwall **62** and 1252 mm (of total value) is located adjacent to the blade tip **64**. The inlet angles, α , and exit angles, β , are further graphically illustrated in FIG. 9.

TABLE 2

α -Metal Inlet Angle (deg) @LE	Z LE (mm) @ LE	β -Metal Outlet Angle (deg) @ TE	Z TE (mm) @ TE
-47.5	810	55	810
-46	838.83	56.3	841.33
-45.5	854.72	56.7	861.87
-44	901.75	57.7	914.8
-40	992.5	59.05	1014.33

-12	1207.24	58.9	1228.65
-6.5	1252	58.6	1252

The portions of the airfoil for the blade **24** described in Table 2 are provided with reference to a Cartesian coordinate system, as discussed above, that has orthogonally related X, Y and Z axes (FIG. 7) with the Z axis extending perpendicular to a plane normal to a radius from the centerline of the turbine rotor, i.e., normal to a plane containing the X and Y values, and generally parallel to the span, S_{B3} , of the airfoil for the blade **24**. The Z coordinate values in Table 4 have 810 mm at a radial location coinciding with the X, Y plane at the radially innermost aerodynamic section of the airfoil for the blade **24**, i.e., adjacent the inner endwall **62**, and are presented as a percentage of the total span of the blade **24**. The X axis lies parallel to the longitudinal axis **32**, and the Y axis extends in the circumferential direction of the engine. Surface profiles at the various surface locations between the distances Z are connected smoothly to one another to form the leading edge section and trailing edge section of the airfoil.

Referring to FIGS. 10-13, a configuration for the fourth stage vane **26** is described. In particular, referring initially to FIGS. 10 and 11, a fourth stage vane airfoil structure **76** is shown including four of the airfoils or vanes **26** adapted to be supported to extend radially across the flow path **13**. Referring additionally to FIG. 12, the vanes **26** each include an outer wall comprising a generally concave pressure sidewall **78**, and include an opposing generally convex suction sidewall **80**. The sidewalls **78, 80** extend radially between an inner diameter endwall **82** and an outer diameter endwall **84**, and extend generally axially in a chordal direction between a leading edge **86** and a trailing edge **88** of each of the vanes **26**. The endwalls **82, 84** are located at opposing ends of the vanes **26** and are positioned at locations where they form a boundary, i.e., inner and outer boundaries, defining a portion of the flow path **13** for the working fluid. Opposing radially inner matefaces **85a, 87a** and radially outer matefaces **85b, 87b** are defined by the respective inner and outer diameter endwalls **82, 84** of the airfoil structure **76**.

FIG. 12 illustrates a cross section of one of the vanes **26** at a radial location of about 50% of the span, S_{V4} (FIG. 10),

along the Z axis of a Cartesian coordinate system that has orthogonally related X, Y and Z axes (FIG. 11), where the Z axis extends perpendicular to a plane normal to a radius from the longitudinal axis **32** of the engine i.e., normal to a plane containing the X and Y axes, and generally parallel to the span, S_{V4} , of the airfoil for the vane **26**. It should be noted that the matefaces **85a, 87a** and **85b, 87b** are shown herein as extending at an angle relative to the direction of the longitudinal axis **32**.

The cross section of FIG. 12 lies in the X-Y plane. As seen in FIG. 12, the vane **26** defines an airfoil mean line, C_{V4} , comprising a chordally extending line at a central or mean location between the pressure and suction sidewalls **78, 80**. At the leading edge **86**, a blade metal angle of each of the surfaces of the pressure and suction sides **78, 80** adjacent to the leading edge **86** is provided for directing incoming flow to the vane **26** and defines an airfoil leading edge (LE) or inlet angle, α . The airfoil inlet angle, α , is defined as an angle between a line 32_P parallel to the longitudinal axis **32** and an extension of the airfoil mean line, C_{V4} , at the leading edge **86**, i.e., tangential to the line C_{V4} at the airfoil leading edge **86**.

At the trailing edge **88**, a blade metal angle of the surfaces of the pressure and suction sides **78, 80** adjacent to the trailing edge **88** is provided for directing flow exiting from the vane **26** and defines an airfoil trailing edge (TE) or exit angle, β . The airfoil exit angle, β , is defined as an angle between a line 32_P parallel to the longitudinal axis **32** and an extension of the airfoil mean line, C_{V4} , at the trailing edge **88**, i.e., tangential to the line C_{V4} at the airfoil trailing edge **88**.

The inlet angles, α , and exit angles, β , for the airfoil of the vane **26** are as described in Table 3 below. The Z coordinate locations are presented as lengths along the total span of the vane **26**. The values for the inlet angles, α , and exit angles, β , are defined at selected Z locations spaced at increments along the span of the vane **26**, where 780 mm (of total value) is located adjacent to the inner endwall **82** and 1400 mm (of total value) is located adjacent to the outer endwall **84**. The inlet angles, α , and exit angles, β , are further graphically illustrated in FIG. 13.

TABLE 3

α -Metal Inlet Angle (deg) @LE	Z LE (mm) @ LE	β -Metal Outlet Angle (deg) @ TE	Z TE (mm) @ TE
32	780	-55.75	780
33.5	860.27	-55.5	850.23
34	923.17	-56.05	925.91
30.5	1039.6	-57	1061.43
15.5	1159.24	-58	1199.19
3	1239.36	-58.5	1297.69
0	1350	-58	1350
-2	1400	-57.24	1400

The portions of the airfoil for the vane **26** described in Table 6 are provided with reference to a Cartesian coordinate system, as discussed above, that has orthogonally related X, Y and Z axes (FIG. 11) with the Z axis extending perpendicular to a plane normal to a radius from the centerline of the turbine rotor, i.e., normal to a plane containing the X and Y values, and generally parallel to the span, S_{V4} , of the airfoil for the vane **26**. The Z coordinate values in Table 6 have 780 mm at a radial location coinciding with the X, Y plane at the radially innermost aerodynamic section of the airfoil for the vane **26**, i.e., adjacent the inner endwall **82**, and are presented as a percentage of the total span of the

vane 26, and are presented as a percentage of the total span of the blade 28. The X axis lies parallel to the longitudinal axis 32, and the Y axis extends in the circumferential direction of the engine. Surface profiles at the various surface locations between the distances Z are connected smoothly to one another to form the leading edge section and trailing edge section of the airfoil.

Referring to FIGS. 14-17, a configuration for the fourth stage blade 28 is described. In particular, referring initially to FIGS. 14 and 15, a fourth stage blade airfoil structure 96 is shown including one of the airfoils or blades 28 adapted to be supported to extend radially across the flow path 13. Referring additionally to FIG. 16, the blades 28 each include an outer wall comprising a generally concave pressure sidewall 98, and include an opposing generally convex suction sidewall 100. The sidewalls 98, 100 extend radially outwardly from an inner diameter endwall 102 to a blade tip 104, and extend generally axially in a chordal direction between a leading edge 106 and a trailing edge 108 of each of the blades 28. A blade root is defined by a dovetail 105 extending radially inwardly from the endwall 102 for mounting the blade 28 to the rotor 30. The endwall 102 is positioned at a location where it forms a boundary, i.e., an inner boundary, defining a portion of the flow path 13 for the working fluid.

FIG. 16 illustrates a cross section of the blade 28 at a radial location of about 50% of the span, S_{B4} (FIG. 14), along the Z axis of a Cartesian coordinate system that has orthogonally related X, Y and Z axes (FIG. 15), where the Z axis extends perpendicular to a plane normal to a radius from the longitudinal axis 32 of the engine i.e., normal to a plane containing the X and Y axes, and generally parallel to the span, S_{B4} , of the airfoil for the blade 28. It should be noted that a central lengthwise axis 107 of the dovetail 105 is shown herein as extending at an angle relative to the direction of the longitudinal axis 32.

The cross section of FIG. 16 lies in the X-Y plane. As seen in FIG. 16, the blade 28 defines an airfoil mean line, C_{B4} , comprising a chordally extending line at a central or mean location between the pressure and suction sidewalls 98, 100. At the leading edge 106, a blade metal angle of each of the surfaces of the pressure and suction sides 98, 100 adjacent to the leading edge 106 is provided for directing incoming flow to the blade 28 and defines an airfoil leading edge (LE) or inlet angle, α . The airfoil inlet angle, α , is defined as an angle between a line 32_P parallel to the longitudinal axis 32 and an extension of the airfoil mean line, C_{B4} , at the leading edge 106, i.e., tangential to the line C_{B4} at the airfoil leading edge 106.

At the trailing edge 108, a blade metal angle of the surfaces of the pressure and suction sides 98, 100 adjacent to the trailing edge 108 is provided for directing flow exiting from the blade 28 and defines an airfoil trailing edge (TE) or exit angle, β . The airfoil exit angle, β , is defined as an angle between a line 32_P parallel to the longitudinal axis 32 and an extension of the airfoil mean line, C_{B4} , at the trailing edge 108, i.e., tangential to the line C_{B4} at the airfoil trailing edge 108.

The inlet angles, α , and exit angles, β , for the airfoil of the blade 28 are as described in Table 4 below. The Z coordinate locations are presented as lengths along the total span of the blade 28. The values for the inlet angles, α , and exit angles, β , are defined at selected Z locations spaced at increments along the span of the blade 28, where 760 mm (of total value) is located adjacent to the inner endwall 102 and 1439

9 mm (of total value) is located adjacent to the blade tip 104. The inlet angles, α , and exit angles, β , are further graphically illustrated in FIG. 17.

TABLE 4

α -Metal Inlet Angle (deg) @ LE	Z LE (mm) @ LE	β -Metal Outlet Angle (deg) @ TE	Z TE (mm) @ TE
-43	760	41	760

8.5	1399	53.08	1399
8.5	1439.9	53.08	1439.9

The portions of the airfoil for the blade 28 described in Table 8 are provided with reference to a Cartesian coordinate system, as discussed above, that has orthogonally related X, Y and Z axes (FIG. 7) with the Z axis extending perpendicular to a plane normal to a radius from the centerline of the turbine rotor, i.e., normal to a plane containing the X and Y values, and generally parallel to the span, S_{B4} , of the airfoil for the blade 28. The Z coordinate values in Table 8 have 760 mm at a radial location coinciding with the X, Y plane at the radially innermost aerodynamic section of the airfoil for the blade 28, i.e., adjacent the inner endwall 102. The X axis lies parallel to the longitudinal axis 32, and the Y axis extends in the circumferential direction of the engine. Surface profiles at the various surface locations between the distances Z are connected smoothly to one another to form the leading edge section and trailing edge section of the airfoil.

It is believed that the vane 22, blade 24, vane 26, and blade 28, constructed with the described average angle changes, provide an improved or optimized flow of working gases passing from the turbine section 12 to the diffuser 34, with improved Mach numbers for the flow passing through the third and fourth stages of the turbine. In particular, the design for the gas-path boundaries and airfoil angles of the third and fourth stages are configured provide a better balance between the Mach numbers for the third and fourth stages, which is believed to provide an improved performance through these stages, since losses are generally proportional to the square of the Mach number.

While specific embodiments have been described in detail, those with ordinary skill in the art will appreciate that various modifications and alternative to those details could be developed in light of the overall teachings of the disclosure. Accordingly, the particular arrangements disclosed are meant to be illustrative only and not limiting as to the scope of the invention, which is to be given the full breadth of the appended claims, and any and all equivalents thereof.

What is claimed is:

1. A turbine airfoil assembly for installation in a gas turbine engine having a longitudinal axis, the turbine airfoil assembly including an endwall for defining an inner boundary for an axially extending hot working gas path, and an airfoil extending radially outwardly from the endwall, the airfoil having an outer wall comprising a pressure sidewall and a suction sidewall joined together at chordally spaced apart leading and trailing edges of the airfoil, an airfoil mean line is defined extending chordally and located centrally between the pressure and suction sidewalls, airfoil inlet and

11

exit angles are defined at the airfoil leading and trailing edges that are substantially in accordance with inlet angle values, α , and exit angle values, β , set forth in one of Tables 1, 2, 3, and 4, where the inlet and exit angle values are generally defined as angles between a line parallel to the longitudinal axis and the airfoil mean line lying in an X-Y place of an X, Y, Z Cartesian coordinate system in which Z is a dimension perpendicular to the X-Y plane and extends radially relative to the longitudinal axis, and wherein each of the inlet and exit angle values is defined with respect to a distance from the endwall corresponding to a Z value that is a distance of a total span of the airfoil from the endwall with the distances being joined smoothly with one another to form a complete airfoil shape.

2. The turbine airfoil assembly of claim 1, wherein the airfoil comprises an airfoil for a third stage vane in a turbine engine, and the one of Tables 1, 2, 3, and 4 defining the airfoil inlet and exit angles is Table 1.

3. The turbine airfoil assembly according to claim 1, wherein the airfoil comprises an airfoil for third stage blade in a turbine engine, and the one of Tables 1, 2, 3, and 4 defining the airfoil inlet and exit angles is Table 2.

4. The turbine airfoil assembly of claim 1, wherein the airfoil comprises an airfoil for a fourth stage vane in a turbine engine, and the one of Tables 1, 2, 3, and 4 defining the airfoil inlet and exit angles is Table 3.

5. The turbine airfoil assembly according to claim 1, wherein the airfoil comprises an airfoil for fourth stage blade in a turbine engine, and the one of Tables 1, 2, 3, and 4 defining the airfoil inlet and exit angles is Table 4.

6. The turbine airfoil assembly of claim 1, including four airfoils comprising, in succession, an airfoil for a third stage vane having the airfoil inlet and exit angles defined by Table 1, an airfoil for a third stage blade having the airfoil inlet and exit angles defined by Table 2, an airfoil for a fourth stage vane having the airfoil inlet and exit angles defined by Table 3 and an airfoil for a fourth stage blade having the airfoil inlet and exit angles defined by Table 4.

7. Third and fourth stage vane and blade airfoil assemblies in a gas turbine engine having a longitudinal axis, each airfoil assembly including:

an endwall for defining an inner boundary for an axially extending hot working gas path, and an airfoil extending radially outwardly from the endwall, the airfoil having an outer wall comprising a pressure sidewall and a suction sidewall joined together at chordally spaced apart leading and trailing edges of the airfoil, an airfoil mean line is defined extending chordally and located centrally between the pressure and suction sidewalls, airfoil inlet and exit angles are defined at the airfoil leading and trailing edges that are substantially in accordance with inlet angle values, α , and exit angle values, β , where the inlet and exit angle values are generally defined as angles between a line parallel to the longitudinal axis and the airfoil mean line lying in an X-Y plane of an X, Y, Z Cartesian coordinate system in which Z is a dimension perpendicular to the X-Y plane and extends radially relative to the longitudinal axis, and wherein each of the inlet and exit angle values is defined with respect to a distance from the endwall corresponding to a Z value that is a percentage of the total span of the airfoil from the endwall, wherein:

12

- a) the inlet angle values, α , and exit angle values, β , for the third stage vane are as set forth in Table 1;
- b) the inlet angle values, α , and exit angle values, β , for the third stage blade are as set forth in Table 2;
- c) the inlet angle values, α , and exit angle values, β , for the fourth stage vane are as set forth in Table 3;
- d) the inlet angle values, α , and exit angle values, β , for the fourth stage blade are as set forth in Table 4.

8. A turbine airfoil assembly for installation in a gas turbine engine having a longitudinal axis, the turbine airfoil assembly including an endwall for defining an inner boundary for an axially extending hot working gas path, and an airfoil extending radially outwardly from the endwall, the airfoil having an outer wall comprising a pressure sidewall and a suction sidewall joined together at chordally spaced apart leading and trailing edges of the airfoil, an airfoil mean line is defined extending chordally and located centrally between the pressure and suction sidewalls, airfoil exit angles are defined at the airfoil trailing edge that are substantially in accordance with exit angle values, β , set forth in one of Tables 1, 2, 3, and 4, where the exit angle values are generally defined as angles between a line parallel to the longitudinal axis and the airfoil mean line lying in an X-Y plane of an X, Y, Z Cartesian coordinate system in which Z is a dimension perpendicular to the X-Y plane and extends radially relative to the longitudinal axis, wherein each the exit angle value is defined with respect to a distance from the endwall corresponding to a Z value that is a distance of a total span of the airfoil from the endwall with the distances being joined smoothly with one another to form a complete airfoil shape, and wherein each the airfoil exit angle is within about 1% of a respective value set forth in one of Tables 1, 2, 3, and 4.

9. The turbine airfoil assembly of claim 8, wherein the airfoil comprises an airfoil for a third stage vane in a turbine engine, and one of Tables 1, 2, 3, and 4 defining the airfoil exit angles is Table 1.

10. The turbine airfoil assembly of claim 8, wherein the airfoil comprises an airfoil for a third stage blade in a turbine engine, and one of Tables 1, 2, 3, and 4 defining the airfoil exit angles is Table 2.

11. The turbine airfoil assembly of claim 8, wherein the airfoil comprises an airfoil for a fourth stage vane in a turbine engine, and one of Tables 1, 2, 3, and 4 defining the airfoil exit angles is Table 3.

12. The turbine airfoil assembly of claim 8, wherein the airfoil comprises an airfoil for a fourth stage blade in a turbine engine, and one of Tables 1, 2, 3, and 4 defining the airfoil exit angles is Table 4.

13. The turbine airfoil assembly of claim 8, including four airfoils comprising, in succession, an airfoil for a third stage vane having airfoil exit angles defined by Table 1, an airfoil for a third stage blade having airfoil exit angles defined by Table 2, an airfoil for a fourth stage vane having airfoil exit angles defined by Table 3 and an airfoil for a fourth stage blade having airfoil exit angles defined by Table 4.

14. The turbine airfoil assembly of claim 8, including at least two of the airfoils comprising, in succession, an airfoil for a third stage blade having airfoil exit angles defined by Table 2, and an airfoil for a fourth stage vane having airfoil exit angles defined by Table 3.
